EXTENDIBLE TOP STRUCTURE FOR TABLES

John J. Wagner, Royersford, and Paul L. Mowrey, Spring City, Pa.

Application September 2, 1933, Serial No. 688,034

4 Claims. (Cl. 45—9)

This invention relates to an extendible top structure for tables, and has for its object to provide, in a manner as hereinafter set forth, a structure of the class referred to for providing when in a non-extended position the top of a small console table and when in extended position a card table top.

A further object of the invention is to provide, in a manner as hereinafter set forth, an extendible table top structure including a stationary body part, two pairs of side leaves hinged to the latter and two pairs of corner leaves, each pair being hinged to one of the pairs of side leaves, and with said leaves so formed to provide, when the structure is in an extended position, that the several leaves are held firmly in place by male and female joints, and when in a non-extended position for the end edges of the side leaves nesting relatively to each other and with the corner leaves being positioned against the inner faces of the side leaves to which they are hinged to form a top of pleasing appearance for a small console table, and when the side and corner leaves are extended with respect to the body part, interengaged with the latter and with each other and secured in extended position providing a card table top of much greater area than the top for the console table.

To the above ends essentially and to others which may hereinafter appear, the invention consists of such parts and such combination of parts which fall within the scope of the invention as claimed.

In the drawings:

Figure 1 is a top plan view of the structure extended to provide a card table top.

Figure 2 is a top plan view of the structure when non-extended to provide a small console top.

Figure 3 is a front edge view of Figure 1 showing the structure extended in full lines and non-extended in dotted lines.

Figure 4 is a section on line 4—4 Figure 1 showing the structure extended in full lines and the side leaves non-extended in dotted lines.

Figure 5 is a section on line 5—5 Figure 1 showing the structure extended in full lines and in dotted lines the console position of the sections.

Figure 6 is an inverted plan view of the structure in non-extended or console top forming position.

Figure 7 is a fragmentary view in section on line 7—7 Figure 1.

Figure 8 is a fragmentary view in section on line 8—8 Figure 1.

The extendible top structure includes a squared stationary body part 1, of an area to constitute the squared top for a small console table and which is anchored in any suitable manner to any form of supporting pedestal, not shown. Hinged as at 2, 3 to the body part 1 are a pair of oppositely disposed side leaves 4, 5 respectively. Hinged as at 6, 7 to the body part 1 are a pair of oppositely disposed side leaves 8, 9 respectively. The leaves 4, 5 when extended are disposed at right angles to the leaves 8, 9. Hinged as at 10 to the ends of the side leaf 4 is a pair of oppositely disposed corner leaves 11, 12. Hinged as at 13 to the ends of the side leaf 5 is a pair of oppositely disposed corner leaves 14, 15. The side leaves are substantially of oblong form and each is of a length greater than the width of body part 1. The corner leaves are square in form and the width thereof is less than the width of the side leaves. The several hinges are arranged on the inner faces of the body part and leaves.

The body part 1 has each of its edges throughout formed to provide the female section of a joint and in this connection said joint section at each of said edges has a squared upper edge part 16 and an inwardly extending lower edge part 17 of arcuate contour of greater height than edge part 16. The edge parts 16 at the ends thereof merge into each other. The edge parts 17 at their ends merge into each other. The edge parts 16, 17 are flush respectively with the upper and lower faces of body part 1.

Each side leaf has its inner corners disposed at opposite inclinations, as at 18, 19. The length of the said inner corners is such to provide the inner side edge 20 of the side leaves of a length corresponding to the width of body part 1. The inner corner edges of the side leaves are disposed at an angle of 45° as indicated at 21, Figure 7. The inner side edge 20 of each side leaf is formed to provide the male section of a joint which cooperates with a female joint section provided by an edge of body part 1 and in this connection the said inner side edge 20 has an upper squared edge part 21 and a lower quarter round edge part 22 which when the side leaf is extended engages in a lower edge part 17 of an edge of body part 1. The upper edge parts 21 of the side leaves, when the latter are extended abut against the upper edge parts 16 of the edges of body part 1. When the side leaves are extended the inclined inner corner edges of the leaves 4, 5 abut the inclined

inner corner edges of the leaves 8, 9 respectively adjacent the corners of body part 1.

Each side leaf 4, 5 has each of its end edges 23, 24 formed to provide the female section of a joint and in this connection, end edge 23 has throughout thereof an outer squared edge part 25 and an inner inwardly extending edge part 26 of arcuate contour. The edge 24 has throughout thereof an outer squared edge part 27 and an inner 10 inwardly extending edge part 28 of arcuate contour. In cross section, edge parts 25, 27 are of less length than that of edge parts 26, 28 in cross sections.

Each side leaf 8, 9 has each of its end edges 15 23', 24' formed to provide the male section of a joint and in this connection each of said ends is formed throughout thereof with an outer squared edge part 25' and an inner quarter round edge part 26' in a manner as shown in Figure 3. The 20 edge parts 26' are adapted to rest in the edge parts 26, 27 when the structure is in non-extended position.

Each corner leaf has its rear edge 29 formed to provide the male section of the joint which 25 cooperates with a female joint section on an end edge of a side leaf 4 or 5, and in this connection rear edge 29 has throughout thereof an outer squared edge part 30 and an inner quarter round edge part 31 which when a side leaf 4 or 30 5 is extended engages in an inner edge part 26 or 28. Each corner leaf has its inner side edge 32 formed to provide the female section of a joint which cooperates (Figure 8) with a male joint section on an end edge of a side leaf 8 or 9, and 35 in this connection inner side edge 32 has throughout thereof an outer squared edge part 33 and an inner inwardly directed edge part 34 of arcuate contour which when side leaf 8 or 9 is extended receives an end edge part 26'. When the side 40 and corner leaves are extended, the edge parts 25, 27 abut edge parts 30, 33, edge parts 26, 28 abut edge parts 31, 33 and edge parts 25', 26' abut the edge parts 33, 34.

The pivots 35 for the hinges 2, 3, 10 and 13 are 45 arranged inwardly with respect to the squared edge parts of the body part 1 and side leaves.

The side leaves have secured to their lower faces at the ends thereof latching devices 36 for the purpose of maintaining the corner leaves extended. The outer edges of the side and corner leaves form flush continuations when the said leaves are extended. The outer edges of the leaves are beveled.

When the structure is in non-extended position, 50 the corner leaves are folded against the inner faces of the leaves 4, 5, the side leaves depend vertically from the body part 1 and the end edges of the side leaves 4, 5 interengage with the end edges of the side leaves 8, 9, whereby a top for a small console table is provided, and with such 55 top being formed with a squared rim. When the structure is in extended position, the inner side edge parts of the leaves interengage with the edge parts of the body part 1 and the rear and inner edge parts of the corner leaves interengage with the edge parts of the ends of the side leaves whereby the outer faces of the leaves and body part are arranged in a flush like manner to provide the card table top. The leaves are maintained extended by the coacting of the latching 60 devices with the corner leaves. The manner of setting up the inner corners of the side leaves provides tight joints at the corner edges when the side leaves are extended. The providing of the 65 body part and leaves with the edge parts as stated 70

form tight joints when the leaves are in extended position.

What we claim is:—

1. An extendible table top structure comprising a square body part, two pairs of extendible oblong side leaves of greater length and less width than the width of and hinged to said body part, the ends of each side leaf extending equal distances beyond a pair of opposite edges of said body part, a pair of extendible square corner leaves of less width than that of each side leaf, hinged to the ends of each leaf of one pair of side leaves and foldable against the inner faces of the latter, latching means carried by the leaves of the other pair of side leaves for maintaining the side and corner leaves extended with respect to said body part, the inner side edges of said side leaves and the edges of said body part being formed with coacting means to provide interengaging tight joints between said body part and side leaves when the side leaves are extended, and the end edges of said side leaves and the rear and inner edges of the corner leaves being formed with coacting means to provide interengaging tight joints between the side leaves and corner leaves when the latter are extended relative to the side leaves. 90

2. An extendible table top structure comprising a square body part, two pairs of extendible oblong side leaves of greater length and less width than the width of and hinged to said body part, the ends of each side leaf extending equal distances beyond a pair of opposite edges of said body part, a pair of extendible square corner leaves of less width than that of each side leaf, 100 hinged to the ends of each leaf of one pair of side leaves and foldable against the inner faces of the latter, latching means carried by the leaves of the other pair of side leaves for maintaining the side and corner leaves extended with respect to said body part, the inner side edges of said side leaves and the edges of said body part being formed with coacting means to provide interengaging tight joints between said body part and side leaves when the side leaves are extended, and the end edges of said side leaves and the rear and inner edges of the corner leaves being formed with coacting means to provide interengaging tight joints between the side leaves and corner leaves when the latter are extended relative to the side leaves. 110

3. An extendible table top structure comprising a square body part, two pairs of extendible oblong side leaves of greater length and less width than the width of and hinged to said body part, the ends of each side leaf extending equal distances beyond a pair of opposite edges of said body part, a pair of extendible square corner leaves of less width than that of each side leaf, 115 hinged to the ends of each leaf of one pair of side leaves and foldable against the inner faces of the latter, latching means carried by the leaves of the other pair of side leaves for maintaining the side and corner leaves extended with respect to said body part, the inner side edges of said side leaves and the edges of said body part being formed with coacting means to provide interengaging tight joints between said body part and side leaves when the side leaves are extended, 120 and the end edges of said side leaves and the rear and inner edges of the corner leaves being formed with coacting means to provide interengaging tight joints between the side leaves and corner leaves when the latter are extended relative to the side leaves, each of said side leaves having the inner corners thereof extending at opposite inclinations, the inner corners of one pair of side leaves abutting the inner corners of the side leaves of the other pair adjacent the corners of the body part when the side leaves are extended. 125

3. An extendible table top structure comprising a square body part, two pairs of extendible oblong side leaves of greater length and less width than the width of and hinged to said body part, the ends of each side leaf extending equal distances beyond a pair of opposite edges of said body part, a pair of extendible square corner leaves of less width than that of each side leaf, hinged to the ends of each leaf of one pair of side leaves and foldable against the inner faces of the latter, latching means carried by the leaves of the other pair of side leaves for maintaining the side and corner leaves extended with respect to said body part, the inner side edges of said side leaves and the edges of said body part being formed with coacting means to provide interengaging tight joints between said body part and side leaves when the side leaves are extended, 130 and the end edges of said side leaves and the rear and inner edges of the corner leaves being formed with coacting means to provide interengaging tight joints between the side leaves and corner leaves when the latter are extended relative to the side leaves, each of said side leaves having the inner corners thereof extending at opposite inclinations, the inner corners of one pair of side leaves abutting the inner corners of the side leaves of the other pair adjacent the corners of the body part when the side leaves are extended. 135

3. An extendible table top structure comprising a square body part, two pairs of extendible oblong side leaves of greater length and less width than the width of and hinged to said body part, the ends of each side leaf extending equal distances beyond a pair of opposite edges of said body part, a pair of extendible square corner leaves of less width than that of each side leaf, hinged to the ends of each leaf of one pair of side leaves and foldable against the inner faces of the latter, latching means carried by the leaves of the other pair of side leaves for maintaining the side and corner leaves extended with respect to said body part, the inner side edges of said side leaves and the edges of said body part being formed with coacting means to provide interengaging tight joints between said body part and side leaves when the side leaves are extended, 140 and the end edges of said side leaves and the rear and inner edges of the corner leaves being formed with coacting means to provide interengaging tight joints between the side leaves and corner leaves when the latter are extended relative to the side leaves, each of said side leaves having the inner corners thereof extending at opposite inclinations, the inner corners of one pair of side leaves abutting the inner corners of the side leaves of the other pair adjacent the corners of the body part when the side leaves are extended. 145

and inner edges of the corner leaves being formed with coacting means to provide interengaging tight joints between the side leaves and corner leaves when the latter are extended relative to 5 the side leaves, each of said side leaves having the inner corners thereof extending at opposite inclinations, the inner corners of one pair of side leaves abutting the inner corners of the side leaves of the other pair adjacent the corners of 10 the body part when the side leaves are extended, and the edge portions of the inner corners being disposed at an angle of 45°.

4. An extendible table top structure comprising a square body part, two pairs of oblong extendible side leaves of greater length than the width of and hinged to the sides of said body part, 15 each of said side leaves having the inner corners thereof disposed at opposite inclinations, the inner side edges of said leaves corresponding in length to the width of said body part, the said 20

inner corners of one pair of side leaves abutting the inner corners of the other pair of side leaves adjacent the corners of said body part when said leaves are extended, said body part and inner edges of said leaves having coacting means to provide a tight joint between the leaves and body part when the leaves are extended, two pairs of corner leaves, each pair of corner leaves being hinged to one of the leaves of one of the pair of side leaves and foldable against the inner faces of the latter, means for latching the corner leaves in an extended position for maintaining the side leaves in a like position, and the end edges of the side leaves and a pair of edges of each of the corner leaves having coacting means to provide a tight joint between the leaves when the latter are extended.
